UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

DESIGN FOR AN ORGAN-CASE.

SPECIFICATION forming part of Design No. 21,349, dated February 16, 1892.

Application filed December 10, 1891. Serial No. 414,625. Term of patent 7 years.

To all whom it may concern:

Be it known that I, FREDERICK W. HEDGELAND, a citizen of the United States, residing in Chicago, in the county of Cook and State 5 of Illinois, have invented a new and original Design in Organ-Cases, of which the following is a specification.

My new and original design relates to the upper or pipe portion of the case-fronts of 10 portable pipe and other organs and is fully shown in the accompanying drawing.

The leading feature of the design consists 15 in the central portion or section formed of ornamental work and the end sections at either side of said central section formed of pipes arranged in rows.

In said drawing, A represents the base or 20 lower part of the organ-case, which, however, forms no part of my present design. The upper or pipe portion of the case consists of the

central ornamental section E and end sections C. The former is preferably formed of open or spindle work *b* and a panel F, and the end sections each consist of a row of pipes. The central section stands out in front of the 25 end sections and the rows of pipes are arranged so as to present round corners at the front of the case, as shown. The rear corners are faced with panel-work D and a suitable cornice or band E extends across the top of 30 the front.

I claim—

The design for the front of the upper or pipe portion of organ-cases, substantially as shown.

FREDERICK W. HEDGELAND.
